UNITED STATES PATENT OFFICE.

OSCAR J. JOHNSON, OF CLOQUET, MINNESOTA.

GARMENT-HANGER.

1,238,781.

Specification of Letters Patent.

Patented Sept. 4, 1917.

Application filed December 1, 1916. Serial No. 134,352.

To all whom it may concern:

Be it known that I, OSCAR J. JOHNSON, a subject of the King of Sweden, residing at Cloquet, in the county of Carlton and State of Minnesota, have invented certain new and useful Improvements in Garment-Hangers, of which the following is a specification.

The present invention relates to improvements in garment hangers designed particularly to accommodate several articles of wearing apparel, being provided for this purpose with separate compactly arranged supporting elements to receive said articles.

The primary object is to provide such a hanger from a single piece of material which is so bent in constructing the device as to form supporting arms to receive, for instance, a coat and vest, and including a clamping frame for trousers, the material being generally twisted so as to adequately strengthen the parts and hold the elements in proper position.

For a full understanding of the present invention, reference is to be had to the following description and the accompanying drawing, in which:

Figure 1 is a front elevation of a device constructed in accordance with my invention.

Fig. 2 is a side elevation thereof.

Fig. 3 is an elevation of a slightly modified form of hanger.

Fig. 4 is a side elevation of the hanger shown in Fig. 3.

Specifically describing the article which forms the subject matter of this invention, it is to be noted as hereinbefore premised that only a single length of wire material is employed in the formation of the device. This wire is so bent as to form a clamping frame 1, a coat support 2 and a vest support 3, referring to the device disclosed in Fig. 1 which elements are arranged one below the other so that all of the articles of clothing are supported by the hanger. The wire in the formation of these separate elements is first bent back upon itself intermediate its length, thus forming the supporting loop or eye 4 at its upper extremity. Each side piece provided by this bending is bent laterally in opposite directions a suitable distance below the loop 4 and then bent transversely to the opposite side and inwardly again to form complementary rectangular frame pieces 5 and 6 constituting the trouser frame 1, above referred to. The side pieces

are twisted about each other at the point 7 and are then carried downwardly together to a point below the bottom of the frame where each piece is again bent laterally and back upon itself to form the corresponding oppositely projecting arms of the coat support 2, whereupon the side pieces are carried downwardly together a suitable distance and finally bent laterally again to form the opposite arms of the vest support 3. The extremities of the side pieces in the formation of this last mentioned element are bent back and brought together at the point 8 where they may be soldered, if desired.

In the formation of the connecting shank portions 9, 9, 9 it is preferable that the side pieces be twisted together and the twisted connections between the several elements 75 are preferably bent as indicated at 10, 10 so as to enable the collar portion of the garment held by the adjacent support to lie smoothly. The supporting arms are also twisted preferably as indicated in the drawing to strengthen the parts. Surrounding the elements of the clamping frame 1 are mounted ring members 11 which are slidable downwardly upon the sides of the frame to provide for clamping an article between 85 said frame members.

In Figs. 3 and 4, I have shown a slightly modified form of the device in that in addition to the elements which have been described above a pair of inclined opposite arms 12 are formed before the formation of the clamping frame, these arms constituting suitable supports for hats or similar articles.

It will be obvious that the hanger is simply formed and by reason of the fact that it is made from a single length of wire, the process of manufacture may easily be carried out at a minimum cost so that the device may be marketed quite cheaply.

Having thus described my invention, what I claim as new is:

1. A garment hanger formed from a single piece of material bent back upon itself intermediate its length and twisted to form 105 a shank and two sides which latter are bent laterally in opposite directions from the shank to form registering frames, each side being returned to and engaged about the shank to form a separate independently 110 movable frame piece, said material being extended downwardly to form a garment sup-

porting member, said frame pieces being inclined relative to the shank to be offset from said member.

2. A garment hanger formed from a single piece of material bent back upon itself to provide a supporting loop at its upper end, the side pieces being twisted to form a shank and then bent laterally in opposite directions and backwardly at an angle to form opposing clamping frames and to engage about the shank, each frame from the shank throughout its entirety being relatively movable with respect to the other frame, said side pieces being then carried downwardly together from said shank to form a second shank from which the side pieces extend laterally to form diametrically opposite supporting arms, said second shank being formed with an offset portion immediately above the arms.

3. A garment hanger formed from a single length of wire bent back upon itself intermediate its length to provide a supporting loop, the side pieces thus formed being twisted together and carried downwardly a suitable distance, then each piece being bent laterally in opposite directions then downwardly and transversely across to the opposite side, then upwardly and back about the twisted portion to form corresponding rectangular frame pieces, the side pieces being then carried downwardly together and twisted, then bent laterally and back upon themselves to form diametrically opposite arms, and clamping rings slidably mounted upon the sides of the frame pieces for imparting clamping action to said pieces when an article is received therebetween.

In testimony whereof I affix my signature.
OSCAR J. JOHNSON.
